UNITED STATES PATENT OFFICE

JOHN W. FARLEY, OF CLEVELAND, OHIO

CUP PLATE FOR PROTECTING ENDS OF PIPE COVERINGS

Application filed March 2, 1931. Serial No. 519,566.

The invention aims to provide an exceptionally simple and inexpensive, yet an efficient and desirable cup plate (hereinafter termed a thimble) for contact with a wall, 5 floor or ceiling around an opening through which a pipe passes, the thimble being adapted to receive the end of a tubular insulator surrounding the pipe. Provision is made whereby the thimble is held against the wall, 10 floor, ceiling or the like, and the pipe insulator merely slides within the thimble incident to expansion and contraction.

Fig. 1 of the accompanying drawing is a sectional view partly in elevation showing 15 four of the thimbles T^1 , T^2 , T^3 and T^4 receiving the ends of insulators I which surround a pipe P passing through walls W^1 , W^2 and W^3 .

Fig. 2 is a vertical sectional view substantially on line 2—2 of Fig. 1 showing the appearance of the thimble T^3 at one side.

Fig. 3 is an elevation showing the opposite side of the thimble T^3 .

Fig. 4 is a vertical sectional view on line 25 4—4 of Fig. 3.

Fig. 5 is a perspective view of one of the thimble-anchoring strips.

Fig. 6 is an elevation of one side of the thimble T^2 .

Fig. 7 is a side view of the thimble T^2 .

Fig. 8 is a sectional view on line 8—8 of Fig. 7.

The thimbles T^2 and T^3 are of slightly different construction, and the thimbles T^1 and 35 T^4 may be considered as following either or both of the structures used in constructing said thimbles T^2 and T^3 .

The thimbles T^2 and T^3 embody certain generic features of construction which will 40 first be described, followed by an explanation of additional structural features possessed by the thimble T^2 . To this end, 10 denotes a circular plate having a laterally turned edge 11 to lie against a wall, ceiling, floor or the like, 45 said plate being provided with a pipe-receiving opening 12 and being divided diametrically of said opening into two sections 13 and 14 which abut each other. Flat splice plates 15 lie against the plate sections 13 and 14 50 within the confines of the laterally turned

edge 11, one end of each splice plate being permanently secured by spot welding 16, while the other end is detachably secured by a screw 17.

A cylindrical collar 18 is secured by spot 55 welded brackets 19 to the outer side of the plate 10 and is spaced outwardly from and disposed in concentric relation with the opening 12, leaving a flat area between the opening and collar adapted to abut an end of the 60 pipe insulator I. The collar 18 is formed of substantially semi-cylindrical sections 20 and 21 having plain ends overlapped circumferentially and secured together by screws 22. By removing these screws and the screws 17, 65 the two sections of the thimble may be disconnected allowing easy application of the thimble after passage of the pipe through the opening in the floor, wall, ceiling or the like, and when said screws are reinserted, the device 70 will be firmly held in assembled condition.

The plate sections 13 and 14 of thimble T^3 , 75 are formed with openings to receive anchoring wires or strips 23, and for illustrative purposes, one plate section is shown provided with an elongated slot 24 whereas the other is formed with a small opening 25.

The thimble T^2 differs from the thimble T^3 , 80 in that it is provided with a sectional cylindrical sleeve 26 at the edge of the opening 12 projecting oppositely from the collar 18, the sections of this sleeve being secured to the sections of the plate 10 by spot welded brackets 27. Near its outer end, the sleeve 26 is 85 formed with suitable openings 28 with which anchors such as 23 may be engaged.

While preferred details of construction have been herein described, it is obvious that within the scope of the invention as claimed, 90 minor variations may be made.

I claim:

1. A pipe insulator cup plate comprising a plate radially divided into sections and adapted to lie against a wall, floor or ceiling, said plate having a pipe-receiving opening and a flat area around said opening adapted to abut one end of a tubular pipe insulator, a cylindrical collar projecting outwardly from said plate in concentric relation with said opening, 100

spaced outwardly from said opening and surrounding said area, whereby said collar is adapted to surround said end of the tubular pipe insulator, said collar being formed of arcuate sections, and means for securing said plate and collar sections in assembled relation.

2. A pipe insulator cup plate comprising a plate adapted to lie against a floor, wall or ceiling, said plate having a pipe-receiving opening and an area around said opening adapted to abut one end of a tubular pipe insulator, said plate being divided diametrically of said opening into two sections having inner edges which directly abut each other, a cylindrical collar projecting outwardly from said plate in concentric relation with said opening and spaced outwardly from the latter around said area to surround said end of the tubular pipe insulator, said collar being formed of two substantially semi-cylindrical sections, said collar sections being secured to said plate sections respectively and having plain ends overlapped circumferentially, and removable fasteners securing said plain overlapped collar section ends together.

3. A pipe insulator cup plate comprising a plate adapted to lie against a floor, wall or ceiling, said plate having a pipe-receiving opening and an area around said opening adapted to abut one end of a tubular pipe insulator, said plate being divided diametrically of said opening into two sections having straight inner edges which directly abut each other, a cylindrical collar projecting outwardly from said plate in concentric relation with said opening and spaced outwardly from the latter around said area to surround said end of the pipe insulator, said collar being formed of two substantially semi-cylindrical sections, said collar sections being secured to said plate sections respectively and having plain ends overlapped circumferentially, removable fasteners securing said overlapped collar section ends together, flat splice plates lying against said plate sections and extending across their abutting edges, means permanently securing one end of each splice plate to one of said plate sections, and a removable fastener securing the other end of each splice plate to the other plate section.

4. A pipe insulator cup plate comprising a plate radially divided into sections and adapted to lie against a floor, wall or ceiling, said plate having a pipe-receiving opening and an area around said opening adapted to abut one end of a tubular pipe insulator, a cylindrical collar projecting outwardly from said plate in concentric relation with said opening, spaced outwardly from said opening and surrounding said area, whereby said collar is adapted to surround said end of the tubular pipe insulator, said collar being formed of arcuate sections, a cylindrical pipe-encircling the edge of said opening and formed of arc-

uate sections, and means for holding said plate, collar and sleeve sections in assembled relation, said sleeve sections having openings near their free ends to receive anchors for holding the plate against a wall, floor or ceiling.

In testimony whereof I affix my signature.
JOHN W. FARLEY.
